A. J. THOMAS

SHOE UPPER AND METHOD OF FINISHING THE EDGES THEREOF

Filed August 29, 1923

Inventor:
Alfred J. Thomas,
by Walter G. Lombard,
Atty..

UNITED STATES PATENT OFFICE.

ALFRED J. THOMAS, OF BRAINTREE, MASSACHUSETTS.

SHOE UPPER AND METHOD OF FINISHING THE EDGES THEREOF.

Application filed August 29, 1923. Serial No. 660,044.

To all whom it may concern:

Be it known that I, ALFRED J. THOMAS, a citizen of the United States of America, and a resident of Braintree, in the county of Norfolk and State of Massachusetts, have invented certain new and useful Improvements in Shoe Uppers and Methods of Finishing the Edges Thereof, of which the following is a specification.

10 This invention relates to methods of finishing the edges of shoe uppers, the object of the invention being the production of a shoe upper with a corded edge, said corded edge being substantially the same thickness

15 as the remainder of the upper.

For the purpose of illustrating the invention, one preferred form thereof is shown in the drawings, this form having been found to give satisfactory and reliable results, although it is to be understood that the various instrumentalities of which the invention consists can be variously arranged and organized, and that the invention is not limited to the precise arrangement and organization of the instrumentalities as herein shown and described, except as required by the scope of the appended claims.

Of the drawings:

Figure 1 represents a sectional plan of a portion of a sewing machine having applied thereto an attachment by which the principles of the present invention may be carried out.

Figure 2 represents a side elevation of the same.

Figure 3 represents a side elevation of the pivoted guide arm.

Figure 4 represents a horizontal section on line 4, 4 on Fig. 3.

Figure 5 represents a side elevation of the adjustable guide member.

Figure 6 represents a horizontal section on line 6, 6 on Fig. 5.

Figure 7 represents a horizontal section of the work support.

Figure 8 represents a vertical section on line 8, 8 on Fig. 7.

Figures 9 to 12 inclusive represent sectional details of the successive positions of the tape and cord until secured to the upper.

Figure 13 represents a perspective of a portion of an upper with a skived edge on its inner face.

Figure 14 represents a perspective of a portion of said upper with the folded tape secured to the edge of its outer face.

Figure 15 represents a perspective of a portion of said upper with the folded tape inturned against the skived inner face, and

Figure 16 represents a perspective of a portion of said upper with the folded tape on its inner skived face and a lining to which said upper and tape is secured by a row of stitches.

Similar characters indicate like parts throughout the several figures of the drawings.

In the drawings, 10 is a cylindrical member or barrel, forming a part of a Singer sewing machine, provided with a reciprocating needle 11, a presser foot 12, and a feed foot 13, all of usual construction and forming no part of the present invention.

To the barrel 10 is secured a bracket 14, having pivoted thereto at 15 a guide formed in two parts 16 and 17, the part 17 being adjustable relatively the part 16.

The bracket 14 has a slot therein through which extend the clamping screws 18. By loosening the screws 18, the bracket 14 may be adjusted horizontally and then secured in adjusted position by turning said clamping screws.

The guide member 16 has a slot 19 there-in concentric to the pivot 15, through which extends a clamp screw 20 to retain said member 16 normally in raised position.

By loosening the screw 20, the member 16 may be moved downwardly about its pivot 15, for the purpose to be hereinafter described.

This member 16 has a lateral flange 21 at its outer end and a tape-receiving opening 22 extending therethrough.

The part 17 of the guide has a tube 23 extending therethrough, the projecting end of which is positioned in the opening 22 and is inclined toward the outer wall thereof.

The tube 23 is adapted to receive a cord 24, which is to be enclosed within a fold 25 of a tape 26 having selvage edges.

This member 17 has its outer end wall 27 so shaped in conformity with the inner wall of the flange 21 that a curved passage will be formed into which the tape 26 is adapted to be fed.

The opposite end of the member 17 is provided with a slot 28 in which are positioned the headed screws 29 threaded to the member 16.

5 By loosening the screws 29, the member 17 may be adjusted relatively to the member 16 so as to accommodate the passage in the guide 16, 17 to different widths of tape 26.

As the tape 26 is fed through the passage 10 in the guide 16, 17, a narrow portion 30 thereof will be folded over to form the fold 25, and as the cord 24 is being fed simultaneously toward this fold 25, it will be positioned in said fold 25 as the tape 26 moves 15 outwardly from the opposite end of said guide passage.

The bracket 14 has a lateral shelf to which is secured a work support 31 consisting of a U-shaped plate, beneath which is disposed 20 a plate 32 having slots 32^x in the inner end thereof, through which slots extend the headed screws 33 for securing the U-shaped plate to the bracket 14.

The inner end of the plate 32 is provided 25 with a flange 33^x by which the plate 32 may be adjusted relatively to the U-shaped plate 31 when the screws 33 are loosened.

The outer end of the plate 32 forms, with 30 the inner wall of the U-shaped bend of plate 31, a slot 34 through which the folded tape 26, with the cord 24 in its fold 25, is fed toward the needle 11, which is adapted to unite the edge of the folded portion 30 to the body portion of the tape 26, with the 35 cord 24 in the fold 25 thereof.

Simultaneously with the feeding of the tape 26 and cord 24, an upper 35 of a shoe is fed toward the needle 11, while resting, inside up, upon the upper face of the U-shaped 40 member or work support 31.

Consequently, the same stitches which unite the fold 25 to the body portion of the tape 26 at the same time unite the tape 26 to the edge of the upper 35.

45 The edge of the upper 35 while feeding, bears against a shoulder 36 on a gage 37, adjustably mounted on the barrel 10, so that the folded tape 26 is secured a uniform distance from the edge of the upper.

50 This gage 37 has a slot 38 in its opposite end through which the clamping screws 39 extend into the barrel 10.

When at the beginning of the operation, it 55 is necessary to insert the tape 26 into its passage in guide 16, 17, and the cord 24 into the tube 23, the member 16 is moved downwardly about its pivot 15 so that the passage and tube will be out of alignment with the slot 34 in the work support 31, thus 60 facilitating the insertion of the tape 26 and cord 24 and permitting the ends thereof to be pulled through the passages therefor.

65 After sufficient lengths of tape and cord have been pulled through the guide 16, 17, these ends are then inserted into the slot 34

in the work support 31, the member 16 being at this time in its lower position, giving free access to the slot 34 of the work support 31.

An opening 40 in the work support 31 is provided, through which a suitable tool may 70 be inserted to assist in feeding the tape through the slot 34 in said work support 31.

The ends thus inserted are then positioned beneath the presser foot 12 and feed foot 13, and the subsequent operation of the sewing 75 machine will then cause the tape 26 and cord 24 to be continuously drawn from the sources of supply.

By means of this mechanism, the tape 26 may be folded with a cord 24 in its fold 25, 80 and then at one operation the folded portion may be secured to the body of the tape 26 and also to the upper 35.

The upper 35 preferably is skived on its inner face at the edge thereof, as indicated 85 at 41 in Fig. 13.

When the tape 26 with the cord 24 in a fold 25 thereof has been secured to the outer face of the skived edge 41 of the upper 35, only one thickness 42 of the tape 26 90 will extend beyond the edge of the upper 35 as shown in Fig. 14.

The skived edge 41 and the under face of the thickness 42 of the tape 26 then have adhesive cement applied thereto, and said 95 single thickness 42 of tape 26 is then turned against the skived face 41.

This inturning of the thickness 42 is preferably along the line of stitches uniting the tape 26 to the upper 35, and when inturned as shown in Fig. 15, a narrow portion of the skived edge 41 is turned in also, extending toward the inturned single thickness 42 of tape 26.

105 By making the fold 25 from a very narrow portion of the tape 26 and leaving substantially only a single thickness of tape to be folded over onto the skived face 41, it makes it possible to have the folded portion no thicker than the body portion of the upper.

110 The lining 43 is then positioned upon the inner face of the upper and is united thereto and to the body of the tape 26 and also the edge of the fold 25 by a row of stitches 44.

115 The tape 26 which is used has selvage edges and as the fold 25 is made, one selvage edge is closely adjacent the cord 24, and during the stitching operation, the needle 11 will pass through the fold 25 between said selvage edge and the cord 24, the stitches thus formed extending through portions of the cord 24 at one side thereof, thus preventing 120 the cord from slipping in the fold.

125 By stitching the fold 25 to the body portion of tape 26, in the manner described, when the single thickness 42 of tape is inturned onto the skived face 41 of the upper 35, no part of the fold 25 will be inter-

posed between said skived edge 41 and single thickness 42 of tape 26, thus making a fold which is of the same thickness as the body of the upper 35.

5. No bulge, therefore, is formed along the edge of the upper 35 which is a great advantage as if a bulge is formed, the beauty of the shoe is greatly marred.

This objection is wholly obviated by embodying the method herein described, and a better finished upper is attained than it has been possible to obtain heretofore where a corded tape is secured to the edge of the upper.

15. The tape 26 is drawn from a source of supply at the right of Fig. 2 so that the tape in passing through the guide 16, 17 will be drawn against the outer end of the member 17 and cause the edge of the tape 26 to commence its fold from the start through the guide 16, 17, the fold 25 being completed when the tape 26 and cord 24 leave said guide 16, 17.

The slot 34 in the work support is tapered, 25 being larger at the end nearest the guide 16, 17, and as the tape 26 with the cord 24 in its fold 25 passes through said slot 34, the fold 25 will be forced tightly against said cord 24 so that when it passes from said slot 30 34 to the needle 11, the selvage edge of the tape 26 will be closely adjacent the cord 24 so that the stitches will pass through the fold 25 between said selvage edge and the adjacent side of said cord 24.

35. When thin material is used for the upper, the same method may be employed without skiving the edge of the upper for, as only a single thickness of tape is interposed between the upper and lining, the additional thickness will be hardly noticed.

A great saving in time is made by simultaneously performing all these operations, and a great advantage is gained inasmuch as no adhesive is required to retain the parts 45 in position until after the folded tape is secured to the upper and this adhesive between the inturned single thickness of tape and the skived portion of the upper may be entirely omitted if desired.

50. It is believed that the operation and many advantages of the invention will be understood readily without further description.

Having thus described my invention, I claim:

55. 1. The method of finishing the edges of shoe uppers which consists in simultaneously feeding a tape, a cord, and an upper having a skived face at one edge, folding a portion of said tape over the cord during the feeding operation, and stitching the folded tape to said upper on its outer face adjacent the skived edge thereof.

60. 2. The method of finishing the edges of shoe uppers which consists in simultaneously feeding a tape, a cord, and an upper having

a skived inner face at one edge, folding a portion of said tape over the cord during the feeding operation, and at the same time uniting the folded tape to said upper on its outer face adjacent the edge thereof by a row of stitches passing through said folded tape contiguous to said cord.

65. 3. The method of finishing the edges of shoe uppers which consists in simultaneously feeding a tape, a cord, and an upper, folding a narrow portion of said tape over upon a wider portion thereof during the feeding operation, feeding a cord into the fold of said tape as it is folded, uniting in one operation said folded portion to the body of the tape and to said upper by a row of stitches, then turning inwardly the body of the tape and the edge of the upper outside said row of stitches, placing a lining upon the inner face of said upper and inturned portions of said tape and upper, and finally uniting said tape, upper, and lining by another row of stitches.

70. 4. The method of finishing the edges of shoe uppers which consists in simultaneously feeding a tape, a cord, and an upper skived on its inner face at one edge, folding a narrow portion of said tape over upon a wider portion thereof during the feeding operation, inserting the cord into the fold of said tape as it is folded, uniting in one operation said folded portion to the body of the tape and to said upper by a row of stitches, then turning inwardly a single thickness of the tape outside said row of stitches onto said skived face, placing a lining upon the inner face of said upper and inturned portion of said tape, and finally uniting said tape, and lining, by another row of stitches.

75. 5. The method of finishing the edges of shoe uppers which consists in simultaneously feeding a tape, a cord and an upper, folding a narrow portion of said tape over upon a wider portion thereof during the operation, inserting said cord into the fold of said tape as it is folded, uniting in one operation said folded portion to the body of the tape and to said upper by a row of stitches, then turning inwardly the body of the tape and the edge of the upper outside said row of stitches, placing a lining upon the inner face of said upper and inturned portions of said tape and upper, and finally uniting said tape, and lining, by another row of stitches adjacent to said cord.

80. 6. The method of finishing the edges of shoe uppers which consists in simultaneously feeding an upper, a tape, and a cord, and at the same time folding a narrow portion of said tape over said cord, uniting the body of the tape and its narrow folded portion to the outer face of said upper by a row of stitches closely adjacent the outer margin of said edge, then turning inwardly a single

thickness of tape outside said row of stitches onto the inner face of the upper, placing a lining on said inner face and inwardly folded thickness of tape, and finally uniting said lining and tape by another row of stitches.

7. The method of finishing the edges of the shoe uppers which consists in simultaneously feeding an upper, a tape and a cord, and at the same time folding a narrow portion of 10 said tape over said cord, uniting at one operation the body of the tape and its narrow folded portion to the outer face of said upper by a row of stitches closely adjacent the outer margin of said edge, then turning inwardly a single thickness of tape outside said row of stitches onto the inner face of the upper, placing a lining on said inner face and inwardly turned thickness of tape, and finally uniting said lining and tape by 15 another row of stitches, positioned between said folded edge of the upper and the cord enclosed within said folded tape.

8. The method of finishing the edges of shoe uppers having their inner faces skived 20 near one edge which consists in simultaneously feeding a tape, cord and upper, and during such feeding operation, first folding a portion of the tape over the cord, and then uniting the folded edge of said tape to the outer face of said upper closely adjacent the outer margin of said skived edge by a single row of stitches.

9. The method of finishing the edges of shoe uppers which consists in simultaneously 25 feeding a tape, cord, and upper, and during such feeding operation, first folding a portion of the tape over the cord, and then uniting the folded edge of said tape to the outer face of said upper closely adjacent the outer 30 margin of said edge by a single row of stitches passing through portions of said cord.

10. The method of finishing the edges of shoe uppers which consists in simultaneously 40 feeding a tape with selvage edges, a cord, and an upper, and during such feeding operation, first folding one selvage edge of the tape over the cord, and then uniting the folded edge of said tape to the outer face of said 45 upper closely adjacent the outer margin of

said edge by a single row of stitches passing through the folded portion of said tape between its selvage edge and the center of said cord.

11. The method of finishing the edges of shoe uppers having a skived inner face at one edge, feeding said upper towards the needle of a sewing machine, simultaneously feeding a tape and a cord, folding a portion of the tape over the cord during the feeding 55 operation, stitching the folded tape to said upper on its outer face closely adjacent the outer margin of said edge, and then turning inwardly a single thickness of the tape and the edge of the upper outside the row of 60 stitches onto the skived inner face of said upper.

12. The method of finishing the edges of shoe uppers having a skived inner face at one edge, feeding said upper towards the 70 needle of a sewing machine, simultaneously feeding a tape and a cord, folding a portion of the tape over the cord during the feeding operation, stitching the folded tape to said upper on its outer face closely adjacent the 75 outer margin of said edge, turning inwardly a single thickness of the tape and the edge of the upper outside the row of stitches onto the skived inner face of said upper, placing a lining upon the inner face of said upper and inturned portions of said tape and upper, and then uniting said tape, upper and lining by another row of stitches.

13. The method of finishing the edges of shoe uppers which consists in simultaneously 80 feeding said upper, a tape, and a cord, and at the same time, inserting the cord in a fold of said tape, and then uniting said tape to the edge of said upper by a row of stitches.

14. The method of finishing the edges of shoe uppers which consists in simultaneously feeding said upper, a tape, and a cord, and folding the tape over said cord during the feeding operation, and then uniting the edges 85 of said tape to the edge of said upper by a row of stitches.

Signed by me at 746 Old South Bldg., Boston, Mass., this 17th day of August, 1928.

ALFRED J. THOMAS.
